GUSTAV F. HOCHRIEM, OF CHICAGO, ILLINOIS

CHECK-CONTROLLED MACHINE

Application filed June 20, 1928. Serial No. 286,782.

This invention relates to check-controlled machines and particularly to a device for delivering coins of different denominations to a machine to effect the operation thereof and for dividing the coins and depositing them according to a predetermined ratio in separate receptacles.

Various types of check-controlled machines are operated on a percentage basis, that is, the owner of the machine divides the receipts with the owner of the location where the machine is exposed. In such machines, the user generally purchases a check which is deposited in the machine and accumulates with other checks. When the machine is opened, a settlement is made on the basis of the checks found therein. Unless both interested parties are present when the machine is opened, some of the checks may be withdrawn surreptitiously and disputes may arise concerning the division of the receipts. Furthermore, where a large number of machines are operated, the owner must depend upon agents and the opportunity for fraud thus afforded often results in serious losses.

It is the object of the present invention to provide a simple and effective device whereby coins may be released by checks introduced to the machine for that purpose, the coins being automatically divided after they have effected the operation of the machine and deposited in predetermined aliquot parts in separate receptacles which are accessible only to the respective parties.

Another object is the provision in a device of this character of a receptacle or receptacles for the aliquot parts which can be withdrawn from the machine and are locked automatically when withdrawn. Other objects and advantages of the invention will be apparent as it is better understood by reference to the following specification and accompanying drawings, in which

Fig. 1 is a vertical section through a device embodying the invention,

Fig. 2 is a section on the line 2—2 of Fig. 1,

Fig. 3 is an enlarged detail in section of the coin-feeding mechanism;

Fig. 4 is a view similar to Fig. 3, illustrating another position of the mechanism;

Fig. 5 is a section on the line 5—5 of Fig. 3,

Fig. 6 is a section on the line 6—6 of Fig. 4,

Fig. 7 is a view similar to Fig. 5 illustrating another position of the operating parts,

Fig. 8 is a section on the line 8—8 of Fig. 5,

Fig. 9 is a section on the line 9—9 of Fig. 6,

Fig. 10 is a section on the line 10—10 of Fig. 7,

Fig. 11 is a section on the line 11—11 of Fig. 5,

Fig. 12 is a section on the line 12—12 of Fig. 6,

Fig. 13 is a plan view of one of the keyed slots through which checks are introduced to the machine,

Fig. 14 is a plan view of one of the checks,

Fig. 15 is a top view of a receptacle adapted to receive the coins, and

Fig. 16 is a section on the line 16—16 of Fig. 2.

The invention may be applied to various types of check-controlled machines in which a check is deposited in a slot provided for that purpose and is thus permitted to control the operation of mechanism within the machine. The particular mechanism thus controlled forms no part of the present invention and therefore will not be described.

The present invention depends upon the feeding of a coin of given denomination to the machine when a corresponding check is introduced. The device may include provision for the introduction of coins of different denominations, and in the example of the invention which is illustrated in the drawings, means is provided for releasing coins of three denominations, for example, quarters, dimes and nickels, when checks of corresponding value are inserted in slots provided to receive them. The coins thus released are permitted to pass the machine, the operation of which is thus initiated, and are then separated into aliquot parts which are

85

90

95

100

deposited in separate receptacles, all of the coins of like denomination being thus segregated in fractional parts predetermined in accordance with the arrangement previously effected between the interested parties. Obviously the device may be adapted to permit the release of coins of larger denomination, and coins of one, two or more denominations may be delivered through the mechanism 10 hereinafter described depending upon the particular purpose of the machine which is thereby controlled.

Referring to the drawings, 5 indicates a housing which is adapted to enclose the 15 mechanism which is divided into coin-delivering, coin-actuated, and coin-separating sections. A partition 6 extends across the upper part of the housing and supports tubes 7, 8 and 9 which in the present form of the 20 invention are adapted to receive respectively a supply of nickels, dimes and quarters. Beneath the partition 6, in which openings are provided corresponding to the tubes 7, 8 and 9 a slide 10 is mounted for reciprocation on a partition 11 which likewise extends across the housing. The slide has an extension 12 which projects from the housing 5 to permit manipulation. Mounted in the slide 10 are three movable plates 13 having openings 14 25 therein which are normally disposed respectively beneath the tubes 7, 8 and 9 and are of a size corresponding to the diameter of the coins in the tubes. One coin of each denomination is thus normally held in the openings 30 in each of the plates 13, and upon reciprocation of the plates these coins may be moved laterally to register with chutes 15, 16 and 17 which permit the coins to fall into the coin-actuated section of the machine. The slide 35 40 10 is provided with a plurality of tongues 18 which, when the slide is actuated, are adapted to project into corresponding openings 19 in each of the plates 13. Consequently the slide may be actuated without moving the plates. Slots 20, 21 and 22 are provided to 45 receive checks which may be purchased or supplied otherwise for that purpose. Each slot is keyed as indicated in Fig. 13 by providing projections 23 adapted to register 50 with grooves 24 (Fig. 14) in the check 25. The position of the grooves 24 determines the value of the checks, that is to say they can be inserted only in the appropriate slot 20, 21 or 22 to release a coin of corresponding 55 denomination. Upon entering the slot the check 25 falls into an opening 26 in the corresponding plate 13 (Figs. 3 to 7) and rests therein in the path of the corresponding tongue 18 on the slide 10. Thereupon 60 when the slide is actuated the plate 13 is advanced and a coin is discharged from one of the tubes 7, 8 or 9. The check is carried forward until it registers with an opening 27 (Fig. 12) through which it falls into one of 65 the chutes 28, 29 or 30 and is conveyed thence

into a receptacle from which the accumulated checks may be withdrawn for further use.

To permit the lapse of sufficient time to effect the transfer of the coin from one of the tubes to the corresponding chute, pawls 31 are pivoted at 32 on the partition 6 and are normally biased by springs 33 toward a rack 34 on each of the plates 13. Pins 35 are adapted to be engaged by cams 36 on the slide, the pawls being thus normally held out of engagement with the racks. When the slide is advanced the pawls 31 are released and if one of the slides 13 is keyed thereto by a check the pawl rides over the teeth of the rack and prevents immediate return of the 80 plate when the slide is withdrawn. When the slide reaches its outermost position, the pins 35 are again engaged by the cams 36, the pawls are lifted, and the plate which has been held by one of the pawls is released. It is returned immediately to its normal position by a spring 37 which is connected to the plate and to the housing. Thus a coin is advanced and is permitted to fall into the corresponding chute as hereinbefore described. In chutes 15, 16 and 17 are shown, 90 diagrammatically only, a possible means for operating the coin-controlled mechanism. In each of the slides, 15, 16 and 17 are slit-like openings, 66, 67 and 68 respectively through 95 which the tips of levers 62, 63 and 64 respectively, extend. These levers are each connected to the respective coin-controlled mechanism which it is desired to actuate and actuate the mechanism when they are depressed by the weight of the coin dropping upon their tips. This is merely diagrammatic and it is obvious that other methods of actuating the coin-controlled mechanism are equally well adapted for use.

In falling through the chute the coin may trip any suitable actuating mechanism to perform the function of the machine, and having accomplished its purpose the coin is delivered by the chute to the separating mechanism which may include wings 38 and 39, pivoted on opposite walls of the enclosing casing 40 and having a connected arm 41 with a counter-weight 42 thereon. A latch 43 is pivoted at 44 on a bracket 45 depending 100 from the casing and is adapted to engage a notch 46 in the arm 41 when the lock is moved in the manner hereinafter described. An arm 47 connected to the latch 43 is disposed in the path of the coins descending 110 through the chute. Separate receptacles 48 and 49 are provided within the housing. Either or both of these receptacles may be removable and may be provided with locking 120 devices as hereinafter described.

The counter-weight 42 is interchangeable with other weights so that the device may be adjusted to afford the desired division of the coins. Thus if one-quarter of the coins are to be deposited in the receptacle 49, the 130

weight should be equal to that of two of the coins. Thus when the parts are in the position indicated in the drawing, the first coin falls upon the wing 39 and rests thereon. The second coin also falls on the wing 39 and balances the counter-weight 42. When the third coin enters the machine the wing 39 is overbalanced and moves, therefore, to permit the coins to fall into the receptacle 48, the notch 46 being engaged at the same time with the latch 43. Thereupon when a coin enters the machine it engages the arm 47 and disengages the latch 43 from the notch 41. The coin is directed by the wing 38 into the receptacle 49. The counter-weight 42 causes the parts to return to the position indicated in the drawing. It will be noted that three of the coins have entered the receptacle 48, whereas one has entered the receptacle 49. The operation continues in the same manner to deposit three-quarters of the income represented by coins of each particular denomination in the corresponding receptacle 48 and one-quarter in the receptacle 49. By changing the weight 42 the division can be made otherwise, as for example if the weight 42 is equal to that of one of the coins, the device will be actuated when two coins fall upon the wing 39 so that two-thirds of the income will be deposited in the receptacle 48 and one-third in the receptacle 49. The arm 47 remains always in the path of the coins entering through the chute and serves to break the fall of the coins, thus preventing actuation of the mechanism as a result of impact of the coins on the wing 39. The accurate division of the coins is thus assured.

It is to be understood that separate means is provided, as indicated in the drawing, for the division of coins of each denomination, and the coins of each denomination are divided, the aliquot parts being deposited in separate receptacles. Thus each of the interested parties upon withdrawing the proper receptacles secures his share of the income of the machine and no question can arise concerning the division of the income. Furthermore, the owner of the machine is assured of immediate payment of all amounts due him, that is to say, he is not called upon to depend upon the credit of the owner of the location. The latter may be required to furnish the coins which are disposed in the tubes 7, 8 and 9, and the owner of the machine secures his share of the receipts immediately by withdrawing the receptacles provided therefor.

To safeguard the contents of such receptacles, particularly in the case where the receptacles are collected by an agent, they may be arranged to be sealed automatically upon withdrawal from the housing. The latter may be provided with doors 50 adapted to be opened by an appropriate key. Each of

the receptacles 48 is thus accessible and can be withdrawn. A closure such as a slide 51 is supported beneath the opening through which the coins enter the receptacle and is connected to a lever 52. The lever is biased by a spring 53 to move the closure to the position indicated in Fig. 15, in which position a flange 54 on the closure engages a spring-pressed locking bar 55 of a lock 56, the closure being thus automatically locked in closed position. The closure is held open when the receptacle is disposed within the housing by a pin 57 depending from the housing through a slot 58 and adapted to engage the lever 52. The slot may be closed by a guard 59 to prevent the escape of coins therethrough. As soon as the receptacle is withdrawn from the housing, the lever 52 follows the pin 57 and the closure is moved quickly to closed position and locked therein. The agent who withdraws the receptacle cannot, therefore, secure access to the coins therein.

As an additional precaution, a card 60 may be supported on the closure 51 and adapted to be exposed through an opening 61 only when the closure is locked in closed position. The card may be signed for example by the owner of the location where the machine is exposed before the receptacle is carried away by the agent.

The receptacle or receptacles may be delivered to the owner of the machine or to a bank where they may be opened to permit withdrawal of the contents.

The device as described insures the efficient operation of machines of the character described and particularly the accurate division of the receipts therefrom. It affords security, moreover, for such receipts. All disagreements concerning division and disposition of the receipts of such machines are avoided, and the owner of the machine is enabled to obtain the maximum profit from the operation thereof.

Various changes may be made in the details of construction and arrangement of the parts of the machine as hereinbefore described, without departing from the invention or sacrificing any of the advantages thereof.

I claim:

1. The combination of a coin controlled machine, means adapted upon the insertion of a check to be actuated to deliver a coin to actuate the machine, receptacles to receive the coins from the machine and means to divert the coin into the receptacles in predetermined proportion.

2. In a check controlled machine, the combination of a means for substituting a coin for a check, a coin controlled mechanism adapted to be operated by said coin, means for delivering the coin from the substituting means to the coin control mechanism and

- an apportioning device for apportioning said coins between a plurality of receptacles.
3. In a check controlled machine, means adapted upon the insertion of a check to be actuated to deliver a coin, a coin operated mechanism adapted to be operated by said coin, receptacles for said coins and means actuated by the weight of said coins to divert the coins into the receptacles in predetermined proportion.
4. In a check controlled machine, means for substituting a coin for a check, a mechanism adapted to be operated by said coin, means for delivering the coin from the substituting means to the coin control mechanism, receptacles to receive the coins, pivoted means actuated by the weight of the coins to divert the coins into the receptacles in predetermined proportion.
- 20 5. In a check controlled machine, means to receive a stack of coins, means for delivering the coins adapted by the insertion of a check to be actuated, and mechanism adapted to be operated by said coins, receptacles to receive said coins and means to divert the coins into the receptacles in predetermined proportion.
- 25 6. In a check controlled machine, means to receive stacks of coins in different denominations, means adapted to substitute coins of the desired denominations for checks of appropriate kind, a mechanism adapted to be operated by said coins, means for delivering the coin from the substituting means to the coin control mechanism, receptacles for the coins, means to divide the coins of each denomination into aliquot parts and to deliver each part to a separate receptacle.
- 30 7. In a check controlled machine, means to receive stacks of coins, check controlled means to deliver coins selectively from the stacks to the machine, receptacles for the coins and means to divert the coins from each stack into separate receptacles in predetermined proportion.
- 35 8. In a check controlled machine, means to receive stacks of coins, check controlled means to deliver coins selectively from the stacks to the machine, receptacles for the coins and means to divert the coins from each stack into separate receptacles in predetermined proportion, including pivoted counterweighted wings, means for holding the wings in one position and means adapted to be actuated by the weight of a coin to release the wings.
- 40 9. In a check controlled machine, means adapted upon the insertion of a check to be actuated to deliver a coin to the machine, receptacles to receive the coins and means to divert the coins into receptacles in predetermined proportion, including pivoted counterweighted wings, means for holding the wings in one position and means adapted to be actuated by the weight of the coin to release the wings.
- 45 10. In a check-controlled machine, having means to receive a stack of coins, a movable slide, a plate movable relatively to the slide adapted to receive a coin from the stack, a chute into which the coin is discharged from the plate, said plate and slide being adapted to be operatively connected by means of a check receptacles to receive the coins; and means to divert the coins into the receptacles in predetermined proportion.
- 50 In testimony whereof I affix my signature.
